UNITED STATES PATENT OFFICE.

WILLIAM M. HUESEMAN, OF DILLSBORO, INDIANA.

COMBINED SLIDE AND BUTTON LOOP FOR OVERALLS.

Application filed June 14, 1924. Serial No. 720,022.

To all whom it may concern:

Be it known that I, WILLIAM M. HUESEMAN, a citizen of the United States, residing at Dillsboro, in the county of Dearborn and State of Indiana, have invented certain new and useful Improvements in Combined Slide and Button Loops for Overalls, of which the following is a specification.

This invention relates to strap fastening devices and more particularly to a combined slide and button loop for employment upon the shoulder or suspender straps of a pair of overalls. Ordinarily, overalls are equipped with button loops which are engageable with the buttons on the bib of the overalls, and the shoulder or suspender straps are provided, in addition to the said loops, with adjustable slides to take up the slack in the said straps. This, however, entails considerable expense, and frequently some little difficulty is experienced in taking up the slack in the shoulder straps. Therefore, the present invention has as one of its important objects to provide, in a single article, means for attaining all of the advantages which are present in the usual button loop and slide, and, at the same time, considerably lessening the cost of the means provided for tensioning and connecting the shoulder straps.

Another object of the invention is to provide a combined button loop and slide which may be readily applied to the shoulder straps of a pair of overalls and may be quickly adjusted to any desired point in the length of the straps, and the loop member then engaged with the respective buttons upon the bib of the garment, further adjustment of the device with relation to the straps being attained at any time desired and without the necessity of disengaging the loop member from the button.

Another object of the invention is to provide a combined slide and button loop for overalls which will not inconvenience or discommode the wearer by rubbing the collar bone or shoulders, as is frequently the case in the use of a separate slide and a separate loop.

In the accompanying drawing:

Figure 1 is a view in front elevation of the combined slide and loop embodying the invention, applied to one of the shoulder straps of a pair of overalls and connected with the button upon the bib of the overalls.

Figure 2 is a vertical sectional view taken

substantially on the line 2—2 of Figure 1, looking in the direction indicated by the arrows.

Figure 3 is a perspective view of the device removed from the shoulder strap.

The article embodying the invention is most clearly illustrated in Figure 3 of the drawing and the same is formed of two pieces of wire, the button loop and a portion 60 of the slide being formed from one piece, and the cross bar of the slide being formed from another piece. The button loop which is indicated in general by the numeral 1, includes a bight 2 which is formed by bending the 65 piece of wire from which the loop is fashioned, at a point substantially midway between its ends, to arcuate form, the side portions of the loop being deflected inwardly 70 toward each other as at 3, to provide the 75 usual restricted throat 4 above the bight. Above the inwardly deflected portions 3, the side members of the loop are outwardly curved as at 5, so as to permit of the ready introduction of the button into the loop, the 80 space between the said portions 5 being greater than the diameter of the button, and the diameter of the bight portion 2 of the loop being of less diameter than the button. At the upper ends of the portions 5 of the 85

button loop, the wire comprising the loop is bent to extend outwardly in opposite directions providing portions 6 constituting the lower sides of the rectangular oblong frame 7 constituting the frame of the slide of the article, the strands of wire being furthermore bent upwardly at right angles to the portions 6 to form the ends 8 of the said frame and being then bent inwardly at right angles toward each other, as at 9, to form the top member of the said frame. The portions 9 are preferably enclosed at and adjacent their ends, by a sleeve 10 which serves to render the upper portion of the frame rigid and prevent relative displacement of the said portions 9.

The bar of the slide is indicated in general by the numeral 11 and is formed from another length of wire which is bent at its ends to provide terminal eyes 12 which slidably engage the end members 8 of the frame of the slide.

In Figure 1 of the drawing, the numeral 13 indicates one of the shoulder straps of a pair of overalls, the numeral 14 a portion of one upper corner of the bib of the overalls, and the numeral 15 the usual button which

is secured to the corner portion of the bib. As illustrated in this figure and in Figure 2 of the drawing, the article embodying the invention is assembled with the shoulder strap by inserting the shoulder strap rearwardly through the frame 7 of the slide and between the lower portion 6 of the said frame and the bar 11, the strap being then passed behind the said bar 11 and upwardly 10 and forwardly and over the top member 9 of the frame. The article is then adjusted along the strap until the desired adjustment is attained, whereupon the button loop is grasped and engaged with the button 15. 15 When so engaged, the strap 13 will be substantially taut, and the pull between the said strap and the bib 14 will result in a tendency of the article to slide downwardly upon the strap, but due to the manner in which the 20 strap is passed about the bar 11 and the top member 9 of the slide frame, the portion of the strap passing between the said bar and said top member of the frame will be frictionally gripped between these parts and, 25 likewise, the portion of the strap which is passed over the forward side of the top member 9 of the frame will be frictionally engaged and pressed rearwardly by the portion of the strap immediately above and in front of the bar 11. It will be evident at this 30 point that the article embodying the invention comprises not only a button loop but also a slide and that it may be adjusted to

any point in the length of the strap 13 so that the desired tension may be imposed 35 upon the strap and the bib of the overalls. By this arrangement, the necessity of providing separate slides and button loops is entirely obviated, thereby effecting a considerable economy in the production of the garment as a whole, it being understood, however, that the article may be adapted to any ordinary pair of overalls in lieu of the slide and button loop heretofore employed. 40

Having thus described the invention, what 45 I claim is:

An article of the class described comprising a body portion formed from a strand of wire bent intermediate its length to provide a U-shaped button receiving loop and having the upwardly extending arms of said loop bent outwardly and then upwardly and inwardly to provide a strap receiving eye extending transversely of said loop and beyond opposite sides thereof, a sleeve fitted upon the inturned end portions of said wire strand to reinforce the upper portion of said eye and retain the said inturned end portions in alinement with each other, and a cross bar extending longitudinally of said eye and 55 having its ends formed into eyes loosely mounted upon the portions of said wire strand at the ends of the eye and mounting the cross bar for vertical sliding movement.

In testimony whereof I affix my signature.
WILLIAM M. HUESEMAN. [L. S.]
